(57) CLAIM

The ornamental design for a merchandise display unit, as shown and described.

DESCRIPTION

FIG. 1 is a front, perspective view of a merchandise display unit showing our new design;

FIG. 2 is a front view thereof, the rear view being identical to the front view;

FIG. 3 is a right side view thereof, the left side view being identical to the right side view; and

FIG. 4 is a top view thereof.

FIG. 5 is a front, perspective view of the merchandise display unit of FIG. 1 with additional environmental subject matter;

FIG. 6 is a front view thereof, the rear view being identical to the front view;

FIG. 7 is a right side view thereof, the left side view being identical to the right side view; and,

FIG. 8 is a top view thereof.

The features shown in broken lines depict environmental subject matter only and form no part of the claimed design. The non-illustrated bottom surface and the unshaded top surfaces also form no part of the claimed design.
